UNITED STATES PATENT OFFICE.

SAMUEL M. SCHROEDER AND JOHN E. NORWOOD, OF BALTIMORE, MARYLAND.

COMBINED HOE AND WEEDEER.

1,156,714.

Specification of Letters Patent.

Patented Oct. 12, 1915.

Application filed April 1, 1915. Serial No. 18,568.

To all whom it may concern:

Be it known that we, SAMUEL M. SCHROEDER and JOHN E. NORWOOD, citizens of the United States, residing at Baltimore, in the State of Maryland, have invented certain new and useful Improvements in Combined Hoes and Weeders; and we do hereby declare the following to be a full, clear, and exact description of the invention, such as will enable others skilled in the art to which it appertains to make and use the same.

This invention relates to garden tools of the combined hoe and weeder type and has for a primary object to obviate certain disadvantages existing in the structure described in United States Letters Patent No. 590,583, dated Sept. 28th, 1897.

In the above designated patented structure considerable difficulty is experienced in firmly locking the band hoe and crust cutter in adjusted relative angular position, due in part to the use of but a single bolt which performs the dual function of a pivot and a lock.

The present invention contemplates the provision of a novel head casting to which the band hoe and crust cutter are so attached as to be easily and quickly adjusted in angular relative positions and then securely locked against displacement.

With the above objects in view the invention consists of certain novel details of construction and combination of parts herein-after fully described and claimed, it being understood that various modifications may be made in the minor details of construction within the scope of the appended claims.

In the accompanying drawing illustrating this invention: Figure 1 is a perspective view of the tool. Fig. 2 is a cross sectional view on the line 2—2 Fig. 1. Fig. 3 is a longitudinal sectional view showing the hoe in one operative position and the crust cutter in one of its released positions. Fig. 4 is a longitudinal sectional view showing the hoe in a different operative position from that shown in Fig. 3 and the crust cutter in a different released position from that shown in Fig. 3.

Referring now to the drawing in which like characters of reference designate similar parts, 10 designates a handle to the lower end of which is attached a head 11 comprising a casting having a longitudinal slot 12 therein and having extensions 13 on the top edges that are formed with arcuate slots 14

that are concentric with bolt openings 15 formed in the sides of the casting and communicating with the longitudinal slot 12. The casting is provided with a ferrule 16 which receives the end of the handle.

The hoe 17 is formed preferably of a single length of strap metal having a straight blade 18, and vertical sides 19 rising from the ends thereof, the upper ends of the sides being bent inwardly as shown at 20 and then straightened to present parallel straight extremities 21 which are passed through the longitudinal slot 12 in the head, such straight extremities being formed with aligned slots 22.

The crust cutter 23 comprises a straight central strip 24 and side strips 25 offset at the lower ends from the central strip, the upper ends of all of the strips being rigidly secured together by welding, riveting or otherwise to produce a straight shank, which is provided with a slot 26.

The shank of the crust cutter is passed in between the shank or straight portions 21 of the hoe with the slots 22 of the hoe shank and the slot 26 of the crust cutter shank registering one with the other, and the shanks of the assembled crust cutter and hoe are then passed into the longitudinal slot 21 of the head 11.

A pivot 27 is passed through the lower ends of the slots 22 and 26 of the hoe and crust cutter respectively and through the openings 15 in the sides of the head 11. A clamp bolt 30 is passed through the upper ends of the slots 22 and 26 of the hoe and crust cutter respectively and through the arcuate slots 14 in the extensions 13 of the head 11, this bolt also having the usual head 31 on one end and being equipped with a thumb nut 32 on the opposite end, the head and nut bearing against corresponding outer faces of the slotted extensions 13.

When the crust cutter and hoe are in a common plane as shown in Figs. 1 and 2, both of these members are rigidly secured against relative movement by means of the two bolts 27 and 30 rather than by means of a single bolt employed in the structure described in Letters Patent No. 590,583, in which latter patent difficulty has been experienced due to unloosening of this single bolt with resultant escape of the hoe and crust cutter from position. The use of these two bolts above described positively prevent such an occurrence.

By referring now to Figs. 3 and 4, it will be seen that the crust cutter may be rocked to released position on either side of the hoe, this being effected by first removing the clamp bolt and rocking the crust cutter to the desired released position then inserting the clamp bolt which prevents return of the crust cutter within the plane of the hoe while at the same time both the pivot and clamp bolt coact in rigidly securing the hoe in operative position. The hoe may be swung on its pivot to various angular operative positions, as for instance, as illustrated in Fig. 4, by loosening the clamp bolt and advancing the latter longitudinally of the arcuate slots 14, and when again tightened both the clamp bolt and the pivot as above described coact in rigidly holding the hoe in adjusted position.

For attaching various tools to the casting 11, a square opening 33 is formed in the end of the casting and a set screw 34 is engaged through the casting and projects into this opening. A variety of tools each having a square shank may thus be engaged in the opening, in the present embodiment a hoe blade 35 being shown as an illustration.

What is claimed, is:—

1. A garden tool comprising a handle, a head mounted on one end of said handle, said head having a longitudinal slot, arcuate extensions on opposite sides of the head formed with arcuate slots registering one with the other and disposed concentrically

with circular openings formed in the sides 35 of said head intermediate the ends of and communicating with said longitudinal slot, a band hoe having slotted shanks disposed within said longitudinal slot, a crust cutter having a slotted shank disposed between the 40 shanks of said hoe, a pivot passed through said circular opening and through the slots of the hoe and the crust cutter, and a clamping bolt passed through said arcuate slots and through the slots of the hoe and crust 45 cutter, whereby the hoe and crust cutter may be locked in adjusted positions at various relative angles.

2. A garden tool comprising a handle, a longitudinally slotted head mounted on the 50 handle, extensions on the head, a band hoe having slotted shanks disposed within the slot, a crust cutter having a slotted shank arranged between the shanks of the hoe, a pivot pin passed through the head and slots 55 of the hoe and crust cutter, and a clamping bolt passed through the extensions and adjustable longitudinally thereof, said bolt being also passed through the slots of the hoe and crust cutter, as and for the purpose set 60 forth.

In testimony whereof, we affix our signatures, in the presence of two witnesses.

SAMUEL M. SCHROEDER.
JOHN E. NORWOOD.
